UNITED STATES PATENT OFFICE.

JOHN Q. SHERMAN AND ALBERT W. METZNER, OF DAYTON, OHIO; SAID METZNER
ASSIGNOR TO SAID SHERMAN.

FLAT-BED MULTICOPY MACHINE.

Application filed June 24, 1920. Serial No. 391,499.

To all whom it may concern:

Be it known that we, JOHN Q. SHERMAN and ALBERT W. METZNER, citizens of the United States, and residents of Dayton, in the county of Montgomery and State of Ohio, have invented a certain new and useful Flat-Bed Multicopy Machine, of which the following is a full, clear, and exact description, reference being had to the drawings forming part of this specification.

Our invention relates particularly to flat bed manifolders wherein continuous webs of paper are drawn over a flat bed, and there held in position, while a type writer, which moves over the bed, makes impressions on the various films, through the interposition of carbon paper or its equivalent.

So far as we are advised no machine in the past has been successful which employed a large number of continuous webs of paper in a manifolding operation, although several designs of machines have been offered on the market and then withdrawn on account of failure. According to our information, all flat bed machines which make large numbers of copies require the use of separate sheets of paper, which must be arranged with interposed carbon sheets, and collated into bundles, having accurate alignment, after which they are clamped to the bed of the machine.

It is our object to avoid this laborious collating as well as the constant error which is likely to creep in through omission of carbon sheets, omission of necessary paper sheets, improper alignment, and the like, and to do this by providing a roll paper machine of the flat bed type.

We have developed in this connection a number of instrumentalities, some of which are an absolute requisite for success in a machine of this type according to our investigations, and some of which improve the operation of such machines.

Among these instrumentalities are the aligning of the sheets laterally, by means of marginal holes or the like punched in the paper of the various webs in accurate relation to the printing thereon, this alignment to be done automatically. We also provide a means for insuring a loose condition of all webs and means for aligning them longitudinally while so loosely held, in combina-

tion with means for maintaining the various strips tightly and flatly against the flat bed of the machine.

We also provide means for an easy, non-frictional passage of the various webs of paper over the carbon paper strips or the like, that may be used, and for jogging the carbon paper loose from the webs of paper, should it become gummy or adherent because of the type impressions therein, thus acting to impede the free longitudinal play of the webs during the longitudinal alignment thereof, and seriously interfering with the pulling-out operation.

Then, too, in connection with the carbon paper and the terminal bar, or tearing off bar, we provide means whereby automatic operated mechanism serves to free the webs of paper from being clamped between tightly bound carbon sheets and whereby the strips are released beneath the tearing off bar to permit the said longitudinal alignment and as an aligning mechanism we employ "jogging" pins, which in co-operation with terminal holes in the individual forms, serve to accurately align the printing on said forms.

We accomplish these various objects and provisions and other advantages to be noted, by that certain construction and arrangement of parts to be hereinafter more specifically pointed out and claimed.

In the drawings,

Figure 1 is a perspective view of the complete device, omitting the rear cabinet.

Figure 2 is a detail perspective of the storage roll rack on which the rolls of paper are to be mounted.

Figure 3 is a detail front elevation of the sliding mechanism in which the carbon paper is held.

Figure 4 is a plan view of one of the sliding frames of the mechanism shown in Figure 3.

Figure 5 is a detail elevation of one of the operating forks for said mechanism.

Figure 6 (Sheet 1) is a detail perspective showing the clamping finger on the type-writer carriage, which presses the paper down at the printing point.

Figure 7 (Sheet 1) is a detail elevation of one of the idler rolls in the lateral adjustment frame.

Figure 8 is a detail elevation, partly in section showing the carbon paper mounting and clamping mechanism.

Figure 9 is an elevation of the carbon paper roll mounting.

Figure 10 is a perspective view of the inner clamping bar element for retaining the carbon paper.

Figure 11 is a perspective view of the removable or "drop in" clamping bar, for the carbon paper.

Figure 12 is a perspective view of the spring plate mounting for the aligning pins on a scale smaller than the other views on Sheet 3.

Figure 13 is a detail vertical section of the machine at the point of attachment of the parts shown in Figure 12.

Figure 14 is a top plan view of the parts shown in Figure 13.

Figure 15 is an end elevation of the parts shown in Figure 14.

Figure 16 is a detail side elevation of one of the controlling cams and paper clamping bars.

Figure 17 is a perspective detail of the guards for protecting the carbon paper and the mounting means therefor.

Figure 18 is a view of one of the pin wheel idler devices for lateral adjustment.

Figure 19 is a perspective detail showing more or less diagrammatically the operation of the carbon paper guards.

Referring first to the frame-work of the machine, it will be observed that the side standards or plates 1, 1, support the typewriter supporting and platen frame 2, 2, over which the typewriter 3 is moved, the construction being similar to any standard form of flat bed typewriters. It will ordinarily be our practice to provide a cabinet of some desired form to enclose the paper mounting and guiding devices at the rear of the standards and guides now referred to. No such cabinet is shown, for purposes of clearness in the drawings.

As shown in Figure 2 (Sheet 2) of the drawings, a rack for mounting the spindles of paper rolls, is provided. The two side bars 4, are connected preferably at the base by a base bar 5. On the one side bar there are cross arms 6, 6, having in each arm a pair of holes 7, 7. There are like cross arms 8, 8, on the other side bar which have angled slots 8^a therein, into which may be dropped the one end of a paper roll spindle 9, the other end being set in the proper hole at the other side of the frame.

Sliding on the bar having the slotted cross arms is another bar 10, which carries a set of segment shaped arms 11. When this bar 10 is in its lower position the arms 11 lie over the slots and keep the roll spindles in place. The bar 10 is provided with a handle 12, which includes in its structure a

hook 13. A latch 14 mounted on the side bar under control of a spring 15 serves to hold the sliding bar 10 in its upper or releasing position.

As shown in Figure 1, there are provided a set of idler rollers 16, one for each paper roll, said idlers being set into the sides of the machine, in any desired way. The paper rolls 17 mounted over the spindles in the rack now described, are ordinarily made up of long webs of paper printed alike into forms, which it is desired to fill out in multiple, all printing being made on each form, in perfect alignment both transversely and longitudinally of the forms.

The webs are brought from the rolls and passed under the idlers, the top and bottom webs only being indicated by the reference letters A and B, the lowermost roll of paper furnishing the uppermost web of paper on the machine platen.

The webs of paper are formed with a set of marginal holes 18, preferably along each margin inside the edge thereof, these holes being punched in uniform and accurate relation to the printing for each strip. Also each form has punched at the forward end thereof, a plurality of holes 19, same being larger, ordinarily than the marginal holes.

As will be noted, the marginal holes are employed for providing a lateral adjustment for the various webs, thereby not only to bring the longitudinal lines on the forms into absolute registry with each other, but also preserving the larger terminal holes 19 into such alignment laterally that it is possible to insert through them suitable aligning pins, after the webs have been drawn over the writing surface of platen.

The large holes 19 are then employed for aligning the webs longitudinally thereby bringing all transverse lines of the webs into accurate registry.

It is readily possible in a multiplicity of webs of paper to have the printing thereon and the holes thereon absolutely uniform in their relation to each other, even though due to the stretching of paper lengthwise and inaccurate lateral cutting, the forms will not be of the same length or width. The use of the holes for aligning in both directions thereby results in a perfect alignment, which so far as we are advised, is not possible in any other way.

As indicative of the usefulness of a large number of copies of the same form, it may be noted that in business houses it is good practice to have the following copies made out as soon as orders are received. (1). Office order for filing. (2). Invoice to be used when goods are shipped. (3). Shop order. (4). Shipping order. (5). Assembly order. (6). Office copy of invoice. (7). Prospective commission estimate. (8). Acknowledgement of order. (9). Credit department

copy of shipment. (10). Sales department copy of commission estimate. (11). Agent's notice of shipment, and (12). Agent's acknowledgement of order.

- 5 As is evident all of these forms require the same information thereon, and the making of the various forms at once upon receipt of the order results in complete advices to every one concerned in the order, 10 and a constant check to each department to avoid error.

After leaving the idler rolls, the paper webs are brought up over the lateral alignment frame, Figure 1. This frame is made 15 up of side bars 20, connected together by pins 21, over which are set rolls 22. These rolls carry at their ends, or possibly at one end only, a series of radial pins 23 of tapered nature and of a size to engage readily 20 into the marginal holes in the paper, successive pins engaging successive holes.

The side bars of the alignment frame are slotted to receive the spindles of rolls or 25 bars 24 (Figure 7) which lie by gravity adjacent the pin bearing rolls, and are grooved as at 25 to clear the pins. These gravity rolls maintain the paper on the pins without pressure against it.

The alignment frame is shown as mounted 30 by clamping bolts 26 on extensions 27 from the sides 2 of the typewriter and bed supporting plates and should preferably be in a slanting position or at least not in a horizontal position, so that the various webs 35 of paper are substantially free of any contact with each other, or at least free of frictional engagement with each other.

Upon passing over the pin bearing rolls in the frame now described, the various webs 40 of paper are brought into alignment laterally because the pin bearing bodies are so arranged that the pin wheel portions are in true alignment and since the holes in the various webs are in alignment also, the paper 45 will be jogged or freely impelled toward a uniform and constant alignment. Instead of a roll having pins at its ends, we may employ in this aligning device a pintle 16^a, over which is mounted a rotatable idler sleeve 16^b 50 (Fig. 18), this sleeve having the pin bearing sprockets 16^c thereon adjustably held by set screws. In order to support the paper webs any desired number of collars or drums 16^d 55 may be mounted on the sleeve and suitably held in place thereon, said collars having a diameter equal to the diameter of the rotary bodies that carry the pins.

With this construction, the pin wheels may 60 be adjusted along the sleeve to any desired spacing and the collars or drums moved accordingly, thereby enabling us to take care of a variety of widths of paper strips.

Without first describing the carbon paper 65 mounting devices, it will be merely noted at this point that the carbon paper in our de-

vice is mounted along-side of the flat bed, and brought in separate sheets across the bed, transversely to the path of the paper and that the paper is inserted between the carbon sheets, and drawn along as the forms 70 are completed and torn off, so that the carbon paper remains in place except from time to time when the strips thereof are pulled across the bed to expose new surface.

In view of the fact that an assembly of 75 say six to twelve paper webs to be written upon, and a like number of sheets less one of carbon paper may have to be dealt with on the platen or bed, it is evident that if there is any rubbing of the paper against the carbon sheets or any roughness around the marginal holes, or the like, that the carbon paper will be caught and pulled out of shape at its edge that opposes the paper movement resulting in loss of time, and 80 making the machine impractical.

In fact it has been our experience that it is not practical to pull a large number of webs of paper through an interlaced transverse body of carbon paper, and have the 90 carbon paper edges exposed to the paper at its point of entrance into the interlaced arrangement.

Accordingly at the rear end of the bed 95 frame or typewriter support 2, we provide channel bars 28 (Figures 17 and 19), which provide a vertical channel along the two side walls of the frame. Into these channels are dropped a series of rods 29 having expanded ends 30, which maintain the body of 100 the rods in spaced relation.

A simple way of forming the expanded ends is to drive small collars on the ends, but any desired way will suffice.

Over the rods are secured a double fold 105 of material, preferably paper as at 31, which engages the rod along the line of fold and thence extends forward over the bed or platen in two plies. There will be enough rods for each sheet of carbon paper used, and 110 the ends of the folds will overlie the sheets of carbon paper 32, thereby protecting the edges of the paper.

The various printed webs may then be 115 brought from the aligning frame, and thence inserted one sheet between each paper guard and drawn over the platen or bed of the machine. This operation is accomplished by drawing the paper films into position on the platen one at a time, setting a piece of carbon paper over each film and dropping in 120 place a guard rod over each film, with the guard strips brought forward and set under and over the carbon paper.

Should it be desired to cut out the transfer 125 of items in certain columns from certain of the multiple copies, the guard sheets will be extended as shown at 33 (Figure 17) so as to block off a portion of the carbon paper sheet which would otherwise effect a transfer 130

on the paper web lying beneath the particular guard in question.

While we mentioned the use of paper, and this because of its thin nature will probably be found preferable, we do not maintain that this is the only practical way of providing a guard for the carbon paper edge. Furthermore there may be many other ways apparent to the persons skilled in the art for 10 guarding the exposed edge of carbon sheets in such an assembly.

As shown in Figures 3, 4, 5, 8, 9, 10, 11, the carbon paper is mounted on rolls at the side of the machine and then brought over 15 the flat platen. Clamping devices for the paper are employed at each side of the machine, which clamping devices are releasable automatically when the typewriter is moved out of writing position, and also are capable 20 of a manual movement longitudinally of the bed, to break the sheets loose from the webs of paper should they adhere thereto and permit their easy adjustment longitudinally of the webs.

25 The rolls 34 of carbon paper are mounted in troughs or spaces 35 along the sides of the bed. Any usual type of spindle 36 is used, which is inserted through a hole in an end plate 37 and over which the carbon 30 paper is placed. A disk 38 on the spindle is under control of a spring 39 around the spindle, and the tapered end 40 of the spindle is inserted in a notch in the block 41. The plate 37 and the block 41 are located 35 adjacent the two ends of the flat platen or bed.

A clamping device for the carbon paper is used at each side of the machine in the troughs 35. Mounted to slide on ledges 42 40 at the base at each side of the trough are frames having side bars 43, 43 and end bars 44. To one end of one of the end bars are secured springs 45, which engage over studs 46 on the end bar, and are held 45 by a cross block, as for example, the block 41. A cross shaft 47 extending through the troughs and beneath the platen and equipped with a handle 48 is employed to slide these frames lengthwise of the platen. 50 This is accomplished by means of U-shaped levers 49 on the shaft and studs 50 on the two side plates of the frames. The outer sliding plate may be held on its seat by removable pins 43^a making the whole assembly 55 readily demountable.

The carbon paper clamps comprise two special plates 51 and 60. The plate 51 is slotted at 52, 52, to ride up and down on studs 53 in the inside plate 43. It has a 60 right angle base flange 54 which is supported by means of suitable springs 55 on a special shelf 56 mounted on said inside frame plate 43 (Figures 3 and 8). Small studs 57 on the base flange 54 serve as retainers for 65 the upper ends of the springs and like studs

58 do the same service for the shelf 56. Terminal slots 59 in the plate 51 may also be used for purposes of permanent attachment to the sliding frame side plate 43.

As held by the springs the plate 51 will 70 have its upper edge normally above the printing surface of the upper sheet of paper on the platen.

A second clamping plate between which and the plate 51 the carbon paper passes is 75 shown at 60, which plate has unitary posts or rods 61 extending therefrom. Over these rods are fitted socket pieces 62, which house springs 63 that press on the ends of the posts. The socket pieces have tapered ends 80 64 which seat in notches cut in the outer sliding plate 43 of the longitudinally moving frame.

The plate 60 seats at the lower end thereof on the base flange of the plate 51, and at 85 its upper end is provided with a hinged plate 65, which is spring-pressed by means of springs 66, lying between the lugs 67 on the plate 60 and the fingers 68 on the hinged plate.

90 It will be understood that a like clamping device is mounted on both sides of the machine, and that the carbon paper passes between the plates 60 and 51 on each side of the lateral troughs bordering the flat bed or platen. The plate 65 overlies the top-most webs of paper on the bed and only when depressed acts as a longitudinal clamp for the material on the bed so that in the absence of a positive forcing downwardly of the assembly the carbon paper will not be held tightly against the bed of the machine, but will be lifted up by means of the upper edge of the plate 51 to a position above the platen or bed.

105 The typewriter 3 which, as is the normal practice, is moved on its tracks entirely to one side of the platen or bed while paper is being changed, carries on its under side a set of rollers 69. As the typewriter is moved into writing position these rollers will contact with the plate 60 and force it downwardly thereby carrying down the carbon paper and stretching it tautly. At the same time the plate 65 will be depressed 110 against the paper lying on the platen and will clamp the paper down in place at the same time. The plate 65 is cut away so as not to interfere with the contact of the rollers with the plate 60 hinged.

115 The purpose of having the hinged plate 65 or some other resilient member to press down on the assembly of paper on the platen is that if the paper is quite thick, the plate would be likely to impede the action of the 120 typewriter by pressing upwardly on the rollers. When resilient, however, it will tip sufficiently to permit the passage of the typewriter, even though the assembly of paper is quite thick, thereby permitting the 125 130

full depression of the carbon paper clamps as well as the use of the desired number of films of paper. For pressing down the paper firmly at the printing point, a spring 5 shaft 3^a is mounted on the carriage 3, same carrying a finger 3^b arranged for contact closely adjacent the type contact.

In any instance the carbon paper will be brought down taut against the platen during 10 the writing on the webs of paper, and as soon as the typewriter is shifted away will become loose with relation to the platen and assist in lifting and loosening the webs and carbon paper from each other.

15 While in this loose condition the handle 48 is rocked to and fro with the result of shifting all of the carbon paper and loosening up all adhesions thereof to the webs. Unless this is done, the operator will have 20 great difficulty in pulling all of the webs together in a forward movement over the bed in order to tear them off and align and set fresh sections of the paper webs in position, should the carbon paper be "sticky" as is 25 often the case.

If it is desired to adjust the carbon paper lengthwise of the platen in order to expose fresh carbon paper to the printing action, an adjusting screw or screws 70 (Figure 4) 30 may be mounted in the end blocks of the troughs and set in different positions so as to co-operate with springs that bring the sliding frame to its normal position in controlling that portion of the carbon paper that 35 is exposed to the type impressions.

Our experience has shown that it is necessary to renew the top sheets of carbon paper sooner than those below, and we have hence worked out a system of mounting the carbon 40 paper whereby it is arranged so that the roll used for the upper sheets shall contain one or two plies, the roll for the next sheets having three or a larger number of plies, and third roll, should one be required, having 45 the remaining necessary plies.

Thus in practice where ten webs of paper are used, the lower five sheets can be on the single carbon roll, the middle three sheets on a single roll and the top two sheets on a single roll. In renewing the paper a fresh portion of the smaller roll is pulled off, say, three times, to two times for the middle roll and one time for the larger roll. This gives us great economy in carbon paper and yet 55 admits of the use of a plurality of plies of carbon paper on a single roll, reducing the requisite size of the carbon paper storage space.

To renew the sheets the plates 60 are lifted 60 out of place, fresh paper drawn off the rolls, the old torn off, and the plates 60 dropped again into place. This can be done without disturbing the webs of paper on the bed of the machine, and avoids the tedious work of

separating and then collating the sheets 65 each time the carbon paper is changed.

Referring now to Figures 12-16 of the drawings, the devices at the operator's end of the machine will be described. It is to be noted of these devices, that they provide 70 for the longitudinal alignment of the various paper webs and the clamping them down to preserve this alignment while being written upon, and for tearing off of the used webs.

75 It should be noted also that if the sheets when they arrive at the operator's end of the machine are not aligned laterally, it will be impossible without an almost complete collating of the various webs to employ the 80 holes 19 in the webs for longitudinal alignment.

All of the webs of paper pass under a tearing off knife or bar 71, which is hinged at one 85 end at 72 on the frame of the platen or bed, and is held clamped down at the other end by means of a spring hook 73. The bar may be readily swung out of the way in order to gain access to the other parts of the machine below it, and to collate the sheets should this 90 be required.

A spring plate 74 is mounted beneath the platen of the machine, with its forward end 95 pressed upwardly by its inherent springiness. Sliding beneath this plate is a three-sided frame 75, which has screws or lugs thereon to engage the slots 76 in the said plate. At the forward end of the side arms of the frame 75 are mounted two pins 77, 100 which extend upwardly and pass through slots 78 in the tearing off bar when in normal position under the influence of the spring plate.

The pins extend downwardly also and are 105 coupled together by a cross rod 79, which may be said to complete the three-sided frame 75. A spring finger 80 mounted beneath the sliding frame and on the spring plate serves to engage the cross rod between the pins and hold them in a retracted position.

A pair of clamps 81 located to the rear of the tearing off knife or elsewhere if desired, are used to clamp the paper in place. These 115 clamps have posts 82 extending down through a frame of the bed, and springs 83 of considerable power press against the heads 84 of these posts and keep the clamps in operative position. A cross shaft 85 having a handle 86 is used to elevate the clamps 120 when desired by means of cams or eccentrics 87 mounted on the shaft and adapted to contact with the heads of said posts.

As so constructed the operation is as follows:—The paper when first set up is brought forward over the bed, the carbon paper inserted between the sheets, and then clamped at both sides, and the sheets aligned 125

longitudinally by hand enough to bring the holes 19 therein into a fair registry.

The operator then lowers the tearing off bar, sets the holes over the pins with the pins through the slots in the bar and grasping the cross rod between them works the pins back and forth, thereby jogging the various webs into line. The pins being considerably smaller than the holes will readily 10 do this.

The webs are loose clear back to the original rolls during this operation and without tearing out the holes, the pins will serve to bring them all into alignment, thereby 15 aligning absolutely the printed matter on the various multiple webs.

It should be understood that this is not a mere pulling of the webs through a short path, which might or might not suffice under 20 specially favorable circumstances, but is a jogging back and forth of loose paper, our whole mechanism being designed for this purpose.

With the aligning pins in their forward 25 position the operator then lets down the clamping fingers, and moves the typewriter into place thereby clamping down the carbon paper and the paper webs along the sides of the machine.

When the writing operation is over, the typewriter is moved away from the bed, thereby loosening the carbon paper, and the forward clamps are manually released by the operation of the handle 86. The carbon 30 paper is then jogged free of adhesion and the pins removed from the paper by forcing the cross rod between them downwardly and rearwardly to bring the pins below the paper and out of alignment with the holes, in which 35 position the cross bar will be retained by the spring hook. The paper is then drawn off, by grasping it in the hand where it extends under the tearing off bar, and tearing it off 40 against said bar. It should be noted of Figures 13, 14 and 15 that if paper were present the aligning pins would be in a lower position because of being blocked off the paper and it should also be noted that when the 45 operator has drawn off a set of forms the next set will be drawn up far enough for the pins to move up into the holes 19 thereof which will stop the operator and guide him in pulling out a proper length form.

Our experience has been that, in the formation of a plurality of webs or films of paper for use in a machine of the above described character, it is impossible or at least impractical to shear the webs at the edges so that they are of uniform width. The 50 variation, even in careful press work is so great as to render manifolding very inaccurate, and so that any device employing the lateral edges of the webs for alignment will really do more harm than good. Our means 55 for aligning the webs laterally by means of

holes punctured in perfect alignment and spacing with regard to the printing on the forms, is thus an essential feature of our machine and is applicable to a wide variety of uses in other paper feeding machines or 60 the like.

We have also no knowledge of any machine for maintaining alignment of films of paper which provides means for jogging the films back and forth for a plurality of movements. Our mechanism for this purpose could, of course, be varied, but we believe it 65 essential to a successful manual alignment of films of paper drawn by hand from storage rolls or the like to jog them back and forth a plurality of times while they are held loosely, so that the jogging can take effect and perfect alignment be produced. This loose holding is, of course, most necessary at all points where the webs are drawn 70 through a bending path.

It is believed that the various steps of operation have been now noted and a set of exemplary devices for accomplishing them pointed out. We do not assert the absolute 75 essentiality of the complete assembly of operative parts and by no means desire to confine ourselves to the specific mechanisms described, but on the contrary desire our claims to be construed with the full application of 80 the doctrine of equivalents wherever their language so permits.

Having thus described our invention what we claim as new and desire to secure by Letters Patent, is:—

1. In a multi-copy machine a storage rack for paper rolls comprising a pair of vertical members, roll spindle engaging means inter-spaced on both sides of said vertical members, and a latching means adapted to engage and hold a plurality of spindles in the spindle engaging means on one of said vertical members, said latching means being operable as a unit.

2. In a multi-copy machine, a storage rack for paper rolls comprising a pair of vertical members, cross arms spaced alike along each of the vertical members, one set of cross arms having holes at each side of their vertical member, and the other set of cross arms having slots spaced and located alike at the said holes, and a member movable on the slotted cross arm vertical member and adapted to close and open said slots for insertion of roll spindles therein.

3. In a multi-copy machine a lateral aligning means for duplicate paper strips adapted to co-operate with a series of holes marginally arranged on the said strips in like relation to the printing thereon, comprising a series of independent rotary idler pin wheel members adapted to engage said holes and positioned alike with relation to each other, there being one pin wheel or more for each strip and a longitudinal aligning means

also adapted to engage holes in the paper at a subsequent point in its path in the machine.

4. In a multi-copy machine, a lateral aligning means for the purpose described comprising idler rotary pin bearing bodies adapted to engage marginal holes in the said strips and a longitudinal aligning means also adapted to engage holes in the paper at a subsequent point in its path in the machine.
5. In a multi-copy machine a lateral aligning means for the purpose described comprising a series of shafts, one shaft for each paper strip to be aligned, and one or more idler rotary pin bearing bodies for each shaft adapted to engage successive marginal holes in one of said paper strips, said pin bearing bodies being arranged in line longitudinally of the path of the strips and a longitudinal aligning means also adapted to engage holes in the paper at a subsequent point in its path in the machine.

6. In a multi-copy machine a lateral aligning means for the purpose described, comprising a series of shafts, one shaft for each paper strip to be aligned, and one or more idler rotary pin bearing bodies for each shaft adapted to engage successive marginal holes in one of said paper strips, said pin bearing bodies being arranged in line longitudinally of the path of the strips, said shafts being so arranged in different horizontal planes that the individual strips of paper may be drawn without contact with each other to an assembly point for multiple writing and a longitudinal aligning means also adapted to engage holes in the paper at a subsequent point in its path in the machine.

7. In a machine of the character described a lateral aligning means for the purpose described comprising a series of shafts, one shaft for each individual paper strip to be aligned, and a pair of rotary idler bearing bodies on each shaft, said bodies being arranged in alignment with each other longitudinally of the path of the strips and a longitudinal aligning means also adapted to engage holes in the paper at a subsequent point in its path in the machine.

8. In a multi-copy machine, a lateral aligning means for the purpose described comprising idler rotary pin bearing bodies adapted to engage marginal holes in the said strips, and means loosely engaging the strips and retaining them down on the pin bearing bodies.

9. In a multi-copy machine a lateral aligning means for duplicate paper strips adapted to co-operate with a series of holes marginally arranged on the said strips in like relation to the printing thereon, comprising a series of independent rotary idler pin wheel members adapted to engage said holes and positioned alike with relation to each other, there being at least one pin wheel

for each strip, and means loosely engaging the strips and retaining them down on the pin bearing bodies and a longitudinal aligning means also adapted to engage holes in the paper at a subsequent point in its path in the machine.

10. In a machine of the character described a lateral aligning means for the purpose described comprising a series of shafts, one shaft for each individual paper strip to be aligned, and a pair of rotary idler bearing bodies on each shaft, said bodies being arranged in alignment with each other longitudinally of the path of the strips, said pin bearing bodies being adjustable along the shafts to take care of different widths of paper and a longitudinal aligning means also adapted to engage holes in the paper at a subsequent point in its path in the machine.

11. In a machine of the character described a lateral aligning means for the purpose described comprising a series of shafts, one shaft for each individual paper strip to be aligned, and a pair of rotary idler bearing bodies on each shaft, said bodies being arranged in alignment with each other longitudinally of the path of the strips, said pin bearing bodies being adjustable along the shafts to take care of different widths of paper, and means adjustable on the shafts for supporting the paper strips intermediate the pin bearing bodies.

12. In a lateral aligning device for the purpose described the combination of a frame, a series of shafts set in said frame at least one rotary pin bearing body mounted on each shaft and adapted to turn idly while engaging marginal perforations in paper strips, there being one shaft for each paper strip, and a series of bars or the like adapted to be mounted in said rack and grooved to provide clearance for the pin bearing bodies and held in position to loosely engage the paper on said pin bearing bodies.

13. In a multi-copy machine, the combination with independent mounting means for a series of rolls of paper strips, a platen upon which the various strips are assembled and held stationary and multiple copies made thereon while so held, and mechanical means for aligning the strips laterally located between the roll mounting means and the platen.

14. In a multi-copy machine, the combination with independent mounting means for a series of rolls of paper strips, a platen upon which the various strips are assembled and held stationary and multiple copies made thereon while so held, and mechanical means for aligning the strips laterally located between the roll mounting means and the platen, said means being adapted to engage a portion of the strips within the edge thereof.

15. An idler lateral aligning device for a plurality of strips of paper, said device being adapted to engage means located within the edges of the strips of paper and a longitudinal aligning means also adapted to engage holes in the paper at a subsequent point in its path in the machine.

16. An idler lateral aligning device for a plurality of strips of paper, said device being adapted to engage means located within the edges of the strips of paper, and comprising a series of elements, one element for each strip of paper and a longitudinal aligning means also adapted to engage holes in the paper at a subsequent point in its path in the machine.

17. The combination in a multi-copy machine of means for supplying continuous webs of paper to be interlaced with transversely extending webs of a transferring medium, of means adapted to lie on both sides of the said web between which said webs of paper pass prior to being brought into contact with said transversely extending webs, said means being adapted to extend over both of the edges of said transversely extending webs, for the purpose described.

18. The combination in a multi-copy machine of means for supplying continuous webs of paper to a printing point, means for mounting transversely extending interlaced pieces of carbon paper between the webs of paper, and means adapted to lie on both sides of the said web of paper and extending over both of the edges of said transversely extending webs of carbon paper, for the purpose described.

19. The combination in a multi-copy machine of means for supplying continuous webs of paper, means for mounting transversely extending interlaced carbon paper strips for said paper and a series of elements also lying between said webs of paper and having ends adapted to extend in the direction of the web paper movement, and lying on both sides of the meeting edge of the carbon paper strips so as to prevent contact of all webs of paper with any edge portion of carbon paper.

20. The combination in a multi-copy machine of means for guarding the edges of interlaced carbon paper, from distortion by the movement of multiple webs of paper therebetween, comprising a series of bars set between the paper webs, and elements extending from said bars and lapping over both sides of said carbon paper edges, so as to prevent contact of all webs of paper with any edge portion of carbon paper.

21. The combination in a multi-copy machine of means for guarding the edges of interlaced carbon paper, from distortion by the movement of multiple webs of paper

therebetween, comprising a series of bars set 65 between the paper webs, and elements extending from said bars and lapping over both sides of said carbon paper edges, said elements comprising double pieces of flexible material secured to said bars and supported between said webs of paper.

22. In a flat bed multi-copy machine, the combination with a platen, a typewriter adapted to move across said platen and strike downwardly with its type against the platen, of means on the typewriter for maintaining a compact condition of multiple webs of the desired print receiving medium beneath the type, comprising a resilient element beneath the typewriter located to press 75 downwardly on the paper closely adjacent the printing point.

23. In a flat bed multi-copy machine, the combination with a platen, a typewriter adapted to move across said platen and strike downwardly with its type against the platen, of means on the typewriter for maintaining a compact condition of multiple webs of the desired print receiving medium beneath the type, comprising a resilient element 85 mounted on and beneath the type writer located to press downwardly on the paper closely adjacent the printing point, said element comprising a spring finger of restricted width so as not to press down on 90 any substantial width of the paper.

24. In a flat bed multi-copy machine, the combination with a platen, a writing machine movable over the platen, means for retaining carbon paper at both sides of the platen, said means being adapted to retain the carbon paper spaced above from the surface of the platen when the writing machine is removed therefrom.

25. In a flat bed multi-copy machine, the combination with a platen, a writing machine movable over the platen, means for retaining carbon paper at both sides of the platen, said means being adapted to retain the carbon paper spaced above the platen 105 surface when the writing machine is removed therefrom and said means being shiftable with relation to the platen so as to loosen adhesions of said carbon paper.

26. In a flat bed multi-copy machine, the combination with a platen, a writing machine movable over the platen, means for retaining carbon paper at both sides of the platen, said means being adapted to retain the carbon paper spaced above the platen 115 surface when the writing machine is removed therefrom, and comprising longitudinally extending members pressed together, and spring pressed above the surface of the platen.

27. In a flat bed multi-copy machine, the combination with a platen, a writing machine movable over the platen, means for re-

taining carbon paper at both sides of the platen, said means being adapted to retain the carbon paper above the platen surface when the writing machine is removed therefrom, and comprising longitudinally extending members pressed together, and spring pressed above the surface of the platen, said writing machine having a contact member adapted to depress said longitudinally extending members to a position to hold the carbon paper tightly down against the bed.

28. A carbon paper arrangement for flat bed multi-copy machines comprising in part a trough element, a plate mounted at one side of the trough element adjacent the bed, and a second plate having means for engaging resiliently the other side of the trough element to retain it in clamping contact with the first plate.

29. A carbon paper arrangement for flat bed multi-copy machines comprising in part a pair of members slideable longitudinally of the bed, a plate mounted on one of said sliding members, and another plate having means for engaging resiliently the other one of the sliding members to retain said other plate in clamping contact with the first plate.

30. A carbon paper arrangement for flat bed multi-copy machines comprising in part a pair of members slideable longitudinally of the bed, a plate mounted on one of said sliding members, and another plate having means for engaging resiliently the other one of the sliding members to retain said other plate in clamping contact with the first plate, and means for moving said sliding members along the bed simultaneously.

31. A carbon paper arrangement for flat bed multi-copy machines comprising in part an element adapted to be moved longitudinally of the bed, and means carried by the said element and adapted to clamp carbon paper for use on the said bed.

32. A carbon paper arrangement for flat bed multi-copy machines comprising in part a trough element, a plate mounted at one side of the trough element adjacent the bed, and a second plate having means for engaging resiliently the other side of the trough element to retain it in clamping contact with the first plate, resilient means for supporting the plate adjacent the bed in such position as to retain its upper edge above the surface of the bed.

33. A carbon paper arrangement for multi-copy machines comprising side supports, a plate on one of said side supports and another plate having posts thereon, and spring housings adapted to slide over said posts, and means in the other side support for removably engaging said spring housings.

34. In a flat bed multi-copy machine, the combination with a platen, and means for clamping carbon paper for use over the

platen comprising relatively fixed plate, and a removable plate, said removable plate having spring means thereon and means for removably supporting the spring means in a position for it to force the removable plate 70 against the relatively fixed plate.

35. An aligning mechanism for multi-copy machines employing continuous webs of paper, comprising pin means for engaging holes in the paper, and means for moving said pins back and forth in a path longitudinal of the continuous strips, said means being limited in movement to a path insufficient to feed a section of paper through the machine. 75

36. The combination in a flat bed multiple copy machine of means for supplying continuous multiple webs of paper thereto, means for loosely retaining webs of paper over the machine bed, said paper having uniformly 80 located holes therein, pin means for engaging the holes, and means for mounting the pin means adapted to permit a limited movement thereof back and forth longitudinally of the machine bed, said movement being insufficient to feed a section of paper through the machine. 85

37. An aligning mechanism for multi-copy machines employing continuous webs of paper forms, comprising pin means for 90 engaging terminal holes in the forms, and means for moving said pins in a limited path back and forth longitudinally of the path of the paper.

38. In a multi-copy machine adapted for 100 use with continuous webs of paper forms having uniform marking thereon and having uniformly located holes both longitudinally and laterally thereof, of pin means for engaging the lateral and longitudinal 105 holes for aligning said webs prior to forming copies thereon.

39. In a multi-copy machine adapted for use with continuous webs of paper forms having uniform marking thereon and having uniformly located holes both longitudinally and laterally thereof, of means for 110 loosely retaining the webs in the machine, and pin means for engaging the lateral and longitudinal holes, for the purpose described. 115

40. In a multi-copy machine adapted for use with continuous webs of paper forms having uniform marking thereon and having uniformly located holes both longitudinally and laterally thereof, of means for loosely retaining the webs in the machine, pin means for engaging the longitudinal 120 holes for effecting lateral alignment of the webs, and additional pin means located to act upon the webs after being laterally aligned and adapted for engagement with the lateral holes to align the webs longitudinally. 125

41. In a multi-copy machine adapted for 130

use with continuous webs of paper forms having marginal holes and transverse holes, of rotary pin idlers to engage the marginal holes, and positively movable pin means adapted 5 to engage the transverse holes, in the webs after same have been laterally aligned, in order to longitudinally align them.

42. In a multi-copy machine, the combination with means for storing continuous 10 multiple webs of paper, means for laterally aligning said webs before reaching the printing bed, a printing bed, and pin means located beyond the bed and adapted to engage holes formed uniformly in the various webs 15 to longitudinally align them.

43. In a multi-copy machine, means for storing continuous webs of paper, means for laterally aligning the webs, means for retaining the webs loosely over a platen, 20 means for loosely retaining carbon paper between the webs over said platen, and pin means adapted for positive reciprocatory movement longitudinal of the platen and adapted to engage holes perforated in the 25 webs of paper for jogging the said webs into alignment during said loose retaining thereof.

44. In a multi-copy machine, means for storing continuous webs of paper, means for laterally aligning the webs, means for retaining the webs loosely over a platen, means for loosely retaining carbon paper between the webs over said platen, and pin means adapted for positive reciprocatory 35 movement longitudinal of the platen and adapted to engage holes perforated in the webs of paper for jogging the said webs into alignment during said loose retaining thereof, and means for clamping tightly to the 40 platen both the continuous webs and the carbon paper, during printing action on the paper.

45. An aligning means for multiple webs of paper over the flat bed of a manifolding 45 machine comprising a plurality of pins, means for mounting said pins for reciprocatory movement, said pins being adapted to engage a plurality of transversely arranged holes formed in the paper webs transversely 50 of the webs, and means for guiding and limiting the said movement of the pins.

46. An aligning means for multiple webs of paper over the flat bed of a manifolding machine comprising a plurality of pins, 55 means for mounting said pins for reciprocatory movement, said pins being adapted to engage a plurality of transversely arranged holes formed in the paper webs transversely 60 of the webs, and means for guiding and limiting the said movement of the pins, comprising a tear off bar arranged to straddle the paper and slotted to receive the pins.

47. In a multi-copy machine, the combination with a storage means for continuous

webs of paper, a lateral aligning means for 65 the webs, means for mounting carbon paper transverse of the webs, means for guarding the rearward edges of the carbon paper from contact with the webs of paper, and longitudinal aligning means for the paper. 70

48. In a multi-copy machine, the combination with a storage means for continuous webs of paper, a lateral aligning means for the webs, means for mounting carbon paper transverse of the webs, means for guarding 75 the rearward edges of the carbon paper from contact with the webs of paper, and longitudinal aligning means for the paper, both of said aligning means comprising pin bearing bodies adapted to engage in holes formed 80 uniformly in the paper.

49. In a multi-copy machine, the combination with a storage means for continuous webs of paper, a lateral aligning means for the webs, means for mounting carbon paper transverse of the webs, means for guarding the rearward edges of the carbon paper from contact with the webs of paper, and longitudinal aligning means for the paper, both of said aligning means comprising pin bearing bodies adapted to engage in holes formed uniformly in the paper, the lateral aligning means being idle and adapted to operate upon pulling the webs thereover and the longitudinal aligning means being positively operable.

50. In a multi-copy machine, the combination with a storage means for continuous webs of paper, a lateral aligning means for the webs, means for mounting carbon paper transverse of the webs, means for guarding the rearward edges of the carbon paper from contact with the webs of paper, and longitudinal aligning means for the paper, said storing means, and lateral aligning means being adapted to individually engaging each web of paper, and maintaining each web separate from the others, both of said aligning means comprising pin bearing bodies adapted to engage in holes formed uniformly in the paper.

51. An aligning means for a plurality of webs of uniformly printed paper, comprising a spring element, a sliding element on the spring element, pins on the sliding element, an element to hold the webs of paper with holes therein loosely over the pins and means for engaging the sliding element to move it to and fro in a line longitudinal of the paper webs.

52. An aligning means for a plurality of webs of uniformly printed paper, comprising a spring element, a sliding element on the spring element, pins on the sliding element, an element to hold the webs of paper with holes therein loosely over the pins and means for engaging the sliding element to move it to and fro in a line longitudinal of

the paper webs and means for positively engaging the paper adjacent the pins, said means being releasable.

53. In a multi-copy machine, means for supplying continuous webs of paper, a support upon which multiple copies are to be made, means between the supplying means and the support for laterally aligning the forms and means beyond the support for 10 longitudinally aligning them.

54. In a multi-copy machine, means for supplying continuous webs of paper, a support upon which multiple copies are to be made, and idler pin bearing rotary means 15 located between the supplying means and the support adapted for engagement with successive holes in the webs for lateral alignment of the webs.

55. In a multi-copy machine, means for 20 loosely retaining a supply of continuous webs of paper, means for loosely and individually aligning said webs laterally, means for supporting the webs for making multiple copies thereof, and means for loosely engaging uniformly arranged holes in the webs 25 for aligning them longitudinally.

56. In a multi-copy machine, means for loosely retaining a supply of continuous webs of paper, means for loosely and individually aligning said webs laterally, means for supporting the webs for making multiple copies thereof, and means for loosely engaging uniformly arranged holes in the webs 35 for aligning them longitudinally, said means for aligning the webs laterally comprising idler pin bearing rotary bodies, adapted to engage holes formed uniformly in the various webs.

57. In a multi-copy machine, means for 40 loosely retaining a supply of continuous webs of paper, means for loosely and individually aligning said webs laterally, means for supporting the webs for making multiple copies thereof, and means for loosely engaging uniformly arranged holes in the webs 45 for aligning them longitudinally, said means for aligning the webs laterally comprising idler pin bearing rotary bodies, adapted to engage holes formed uniformly in the various webs, said idlers being set out of line 50 with the means for supporting the webs, whereby they are frictionally free in their movement therefrom to the said support.

58. In a flat bed multi-copy machine, the 55 combination with a platen, a writing machine movable over the platen, means for retaining carbon paper at both sides of the platen, said means being adapted to retain the carbon paper spaced above the platen 60 surface when the writing machine is removed therefrom, and to bind it down tightly against the platen when the writing machine is in writing position.

59. The combination in a multi-copy ma-

chine of means for supplying continuous webs of paper to be interlaced with transversely extending webs of a transferring medium, of web-like means between which said webs of paper pass prior to being brought into contact with said transversely extending webs, said means being adapted to extend over the edges of said transversely extending webs, and thence along the under surface of the transferring medium to a point beneath the printing surface of the continuous webs to block off a transfer at selected points. 75

60. The combination in a multi-copy machine of means for supplying continuous webs of paper to a printing point, means for mounting transversely extending interlaced pieces of carbon paper between the webs of paper, and web-like means lying between the webs of paper and extending over the edges of said transversely extending webs of carbon paper, and thence along the under surface of the carbon paper to the desired degree to a point beneath the printing surface of the continuous webs to block off a transfer at selected points. 80

61. The combination in a multi-copy machine of means for supplying continuous webs of paper, means for mounting transversely extending interlaced carbon paper strips for said paper and a series of web-like elements also lying between said webs of paper and free at the side edges and having ends adapted to extend in the direction of the web paper movement, and thence along the under surface of the carbon paper strips to the desired degree for blocking off 85 transference from the desired portions of underlying paper webs. 90

62. The combination in a multi-copy machine of means for guarding the edges of interlaced carbon paper, from distortion by the movement of multiple webs of paper therebetween, comprising a series of bars set between the paper webs, and elements extending from said bars and lapping over both sides of said carbon paper edges, said elements extending thence along the surface of the carbon paper to a point beneath the printing point of the machine, and said elements comprising double pieces of flexible material secured to said bars and supported between said webs of paper. 105

63. The combination in a multi-copy machine of means for guarding the edges of interlaced carbon paper, from distortion by the movement of multiple webs of paper therebetween, comprising a series of bars set between the paper webs, and elements extending from said bars and lapping over both sides of said carbon paper edges, said elements comprising double pieces of paper secured over the bars and supported between said webs of paper, with the outer edges of the pieces cut with the desired extensions to 110 115 120 125

block off carbon paper transference to the desired degree.

64. In a multi-copy machine adapted for use with continuous webs of paper forms having uniform marking thereon and having uniformly located holes both longitudinally and laterally thereof, of pin means for engaging the lateral and longitudinal holes for aligning said webs prior to forming 10 copies thereon, said holes being larger than the pins.

65. In a multi-copy machine adapted for use with continuous webs of paper forms having uniform marking thereon and having uniformly located holes both longitudinally and laterally thereof, of means for loosely retaining the webs in the machine, and pin means for loosely engaging the lateral and longitudinal holes, for the purpose 20 described.

66. In a multi-copy machine adapted for use with continuous webs of paper forms having uniform marking thereon and having uniformly located holes both longitudinally and laterally thereof, of means for loosely retaining the webs in the machine, pin means for loosely engaging the longitudinal holes for effecting lateral alignment of the webs, and additional pin means located 25 to act upon the webs after being laterally aligned and adapted for loose engagement

with the lateral holes to align the webs longitudinally.

67. In a multi-copy machine in which a plurality of webs of paper are to be manually grasped, and pulled through the machine, aligning means for longitudinal alignment comprising a pin bearing means having a pin or pins to engage holes in the paper, said means being mounted so as to permit of repeated movement to and fro in a path longitudinal of the paper, but of less length than would accomplish a feeding of the paper.

68. In a multi-copy machine in which a plurality of webs of paper are to be manually grasped, pulled through the machine, and aligning means for longitudinal alignment comprising a pin bearing means having a pin or pins to engage holes in the paper, said means being mounted so as to permit of repeated movement to and fro in a path longitudinal of the paper and a lateral aligning means comprising idler pin bearing bodies adapted to engage holes in the paper whereby the holes for the first mentioned pin bearing means will be capable of use without repeated collation of the paper web.

JOHN Q. SHERMAN.
ALBERT W. METZNER.
